UNITED STATES PATENT OFFICE.

WILLARD C. BRINTON, OF NEW YORK, N. Y.

FREIGHT-HANDLING APPARATUS.

Application filed May 5, 1920. Serial No. 378,990.

To all whom it may concern:

Be it known that I, WILLARD C. BRINTON, a citizen of the United States of America, and a resident of New York, city, county, 5 and State of New York, have invented certain new and useful Improvements in Freight-Handling Apparatus, of which the following is a specification.

This invention has for its general objects 10 the provision of simple and practical apparatus for handling freight, both in warehouses and the like, and on the road.

A special feature of the invention is a 15 carrier platform which is detachably engageable with the motor truck of the apparatus and which embodies numerous novel points of construction, arrangement and relation of parts, and which in particular is so designed that it is reversibly engageable end for end with respect to the motor truck, and is so constructed that the thrust exerted by the lifting jacks of the truck will 20 be distributed throughout the platform regardless of the disposition of the load on 25 the platform.

Another feature of the invention relates 30 to the short-turning gear of the truck enabling it to round sharp corners or to enter restricted places for instance for the purpose of getting beneath a loaded platform which it may have been necessary to load in 35 a relatively unhandy or inconvenient position.

Another feature is the provision of elastic 40 bumper mechanism between the truck body and platform and which will absorb the shock and prevent injury to the parts when the truck is run into position beneath a loaded platform.

Other features relate to details in the 45 construction of the platform including the manner in which it is braced and supported, and the means which enables an unloaded or lightly loaded platform to be trundled about, and which means, however, does not 50 destroy the normal immobility of the platform when, for instance, it is being loaded and it is desirable that it shall stand firmly in place.

Various other features of the invention 55 will appear as the specification proceeds and will be more fully understood from a consideration of the accompanying drawings forming a part of the specification, and in

which I have illustrated the invention embodied in several different commercial forms.

In the drawings referred to:

Figure 1 is a side view of a form of the apparatus designed particularly for use in 60 warehouses and the like.

Figure 2 is a plan and more or less diagrammatic view illustrating particularly the short-turn feature of the apparatus.

Figure 3 is an end view of one of the 65 carrier platforms.

Figures 4 and 5 are side and end views respectively of one of the platforms in the loading position supported on its own legs.

Figure 6 is a side view of a longer base 70 platform.

Figure 7 is a side elevation illustrative of a modification of this longer base platform.

Figure 8 is a side view of the invention 75 as embodied in a road vehicle for long haul work.

Figure 9 is an end view of the loading platform in this last construction, and which has the form of a closed compartment or van 80 body.

Figures 10, 11 and 12 illustrate the parts of one form of interposed shock absorber or cushioning mechanism.

Figure 13 is a vertical sectional view of 85 the same.

Figures 14 and 15 are enlarged plan and side views respectively of one of the carrier platforms, drawn particularly to illustrate the method of bracing and distributing 90 the load supported thereby.

Figures 16 and 17 are end and vertical sectional views respectively illustrating the connection between the supporting legs and the cross struts or beams.

Figures 18, 19 and 20 are broken detail views partly in section illustrating a form 95 of ball caster construction as a substitute for the wheel casters provided at one end of the platform in the first constructions 100 shown.

In the warehouse type of apparatus disclosed particularly in Figures 1 and 2, the motor truck 25 is made with a relatively short wheel base and is equipped with four 105 supporting wheels 26, all motor driven and arranged to swing in pairs as clearly shown in Figure 2.

These motor wheels may be of the type disclosed in my former applications, particularly the one filed April 10th, 1918, Serial No. 227,834, wherein, each wheel carries and is directly operated by an electric motor 27, the frame of the motor being pivoted to the frame of the truck on an axis 28 and the front and the rear motor wheel units being connected in pairs and coupled to the steering mechanism, the control of which is here represented by the hand wheel 29, in such a way that when the front wheels are turned at one angle, the rear wheels will be turned at the reverse angle. This produces the result depicted in Figure 2, which makes it possible to swing the truck in a very small space and to negotiate sharp and restricted corners. The connections from the steering wheel are not illustrated in the present case, but may be similar to the ones disclosed in the application referred to and arranged to swing the front and rear motor driven wheels at opposite angles.

25 The truck illustrated is provided with an end wall or "dash" 30, with an operator's platform 31 and with suitable controller mechanism 32.

The carrier platform which forms the 30 demountable body of the apparatus is preferably constructed as illustrated particularly in Figures 14 and 15, with longitudinal side beams or sills 33 carrying a suitable flooring and connected at intervals by the 35 cross beams or struts 34.

For the cross beams I prefer to use channel irons, as illustrated. These beams are so located as to form seats or bearings for the plungers 35 of the elevating jacks 36 40 of the truck (see particularly Figures 1 and 8) and they are connected with the side sills in such a way as to distribute the load substantially equally over the platform. The cross channels 34 may be connected with 45 the side sills by through bolts, such as I have shown at 37 in Figures 14 and 15. This method of fastening is particularly applicable to certain of the intermediate and end channels, as illustrated in these views, 50 but others of the cross channels are secured to the sills through the intermediary of the supporting feet.

These supporting feet or legs are of novel construction, in that they are made in the 55 form of trusses or arches connected at their ends with the side sills and cross beams, and further, in that they are constructed of channel iron. Also, the feet at one end of the platform are preferably formed with 60 substantially flat shoes to frictionally engage the supporting structure and form brakes, preventing shifting of the platform during loading, while the feet at the opposite end are provided with wheels or 65 casters, enabling the platform, when empty

or lightly loaded, to be lifted at the other end and be pushed about to suit special requirements.

The feet for the fixed end of the truck are shown in Figures 14 and 15 as each 70 constructed from a single length of channel iron, having downwardly convergent straight side portions 38 and 39, a relatively short flat connecting portion 40 forming a bearing foot and brake, the side portion 75 38 receiving the end of the side sill 33 and being secured thereto by through bolts 41 and the other side portion 39 having a part of the back 42 cut out from between the sides thereof and bent under to support the 80 lower edge of the sill, the separated side portions of the channel being bolted over the sides of the sill by fastenings 43. In constructing the truss, the side sills of the channel are simply notched at the points 44, 85 said notches being closed up as indicated when the side portions 38 and 39 are bent back with respect to the foot portion 40.

Connection is made between the leg trusses and the cross braces by bending portions 45 of the side walls of the channel members 38 and 39 at the upper ends thereof over into the ends of the channels in the cross braces (see also Figure 16), and then welding such bent-over portions integrally to the cross channels. This construction thus provides a rigid tie between the cross braces, the sills and the supporting feet.

The feet for the opposite end of the platform are shown as similarly constructed and connected with the side sills and cross channels, but in the form first illustrated, as having the inclined sides thereof connected by separately formed connecting elements 46 provided with bearings for the rollers or casters 47.

In Figures 18, 19 and 20 I have illustrated a form of ball-caster, comprising a supporting ball 48 backed up by bearing balls 49 seating in a socket formed in a casting 50 secured by suitable fastenings 51 to the bottom or connecting portion 40 of one of the trusses, said trusses being, in this instance, similar to the ones provided for the stationary end of the platform, except for the fact that the connecting part 40, instead of acting as a brake shoe, is provided with an opening 52 therethrough, through which the supporting ball projects. A further feature of this caster is that the bearing balls are secured in their seat by a confining plate or washer 53 seating in a recess 54 in the lower face of the block or casting 50 and confined by said block against 115 the upper face of the channel portion 40.

This confining plate is shown as having a central opening through which the supporting ball projects and which is somewhat less than the greatest diameter of the ball and is 120 125 130

disposed below the center of the ball, so as to confine the supporting ball in its socket.

The form of caster construction just described is practically frictionless and is particularly advantageous in that it enables the making of the supporting feet all alike and simply securing the casters in those feet which are to be applied to the movable end of the platform.

10 In order that the carrier platforms and trucks may be assembled in either end to end relation, I have spaced the cross channels 34 in such a way as to cause them to stand in line with the elevator plungers, no matter which end of the platform the transporting truck is run under.

The simplest illustration of this idea is given in Figure 1, wherein, the line A represents the distance between the elevator

20 plungers and in which it will be seen that the distance A' between the cross channel 34 at one end of the platform and the cross channel 34^a which is located inward from the opposite end of the platform is equal

25 and corresponds to the distance A² between the cross channel 34^b at said opposite end of the platform and the cross channel 34^c inward from the first end of the platform.

Thus, no matter under which end of the 30 platform the truck is shifted, one of the end cross channels and one of the intermediate cross channels will stand in position to be engaged by and to receive the thrust of the elevating jacks. This means that the trucks

35 can be engaged beneath either end of a platform, to suit circumstances, and also that, in either relation of the parts, the strain will be distributed substantially equally and without racking or twisting the platform

40 because of localization of the weight thereon.

The platform shown in Figures 4 and 5 is similar to the one just described, except that it is provided at the wheeled end thereof with a platform extension or overhang 55,

45 corresponding in length to the length of the platform at B extending beyond the supporting cross channel 34^a near the opposite end of the platform. The distance A' between the cross channels 34 and 34^a corresponds to the distance thus marked in Figure 1, and as the projection of the platform beyond the supported cross channels is equal at opposite ends of the platform, the platform may be reversibly supported on the truck and the same cross channels in each instance will be engaged by the lifting jacks.

55 The carrier platform may be lengthened and otherwise modified so long as this relation of the spacing of the cross channels at the opposite ends of the platform is maintained. Thus, in the lengthened platform shown in Figure 6, an additional cross channel 34^d is interposed between the leg engaged

60 channels and the spacing A' between this channel and channel 34 corresponds to the

distance between the plungers so that these channels will be engaged when the platform is placed with the overhang 55 at the head of the truck, the cross channels 34^c and 34^a being spaced a distance A² so that these will be engaged by the jacks when the platform is arranged with the overhang at the tail end of the truck.

In further lengthening out the platform, as shown in Figure 7, there may be provided an additional cross channel 34^e at the overhang end of the platform to provide the spacing A' between cross channels for engagement with the lifting jacks, the spacing A² between the other cross channels 34^a and 34^c being preserved for the engagement of said cross channels with the jacks in the reverse relation of the platform.

In Figure 8 I have shown how the invention may be applied to a commercial form of 85 motor driven road vehicle 56, the same being equipped with lifting jacks 36 and the platform, in this instance, being in the form of a closed van 57. In this construction, also, the same relation of the cross sills is retained, 90 the distances A' and A² between the supporting cross channels being equal so that the truck and the platform may be relatively reversed.

It is important that the truck should be 95 fully entered beneath the platform, so as to insure the registry of the lifting jacks with the cross beams. This is usually accomplished by running in the truck under the platform as far as it will go, or until the 100 head-board or dash brings up against the adjacent end of the platform. With a heavily loaded platform and a relatively heavy truck, the engagement of these parts is liable to be quite forceful and might be such as to 105 injure one or the other of these members. To prevent this, I have interposed a shock absorber consisting in the first form, as shown in Figure 8, of reversely bent hairpin springs 58 attached to the back of the 110 cab or head-board with free arms extending vertically in position to be engaged by the adjacent end of the platform, said free spring ends being of sufficient vertical extent to allow for the vertical adjustment of 115 the van with respect to the truck body.

The shock absorber also may be constructed as shown in Figures 10 to 13, wherein, 59 designates a base member secured, for instance, on the truck frame or back of the 120 cab and chambered to receive a block 60 of rubber or other suitable cushioning material and which is covered by a guard 61.

This guard may be made of heavy sheet metal and is shown as provided at its inner 125 lower corners with lugs 62 which can be engaged in back of the outstanding lugs 63 at the forward lower edges of the base 59, after which the cover may be rocked back on the lugs 62 and 63 as a hinge, the out- 130

standing lugs 64 at the upper forward edges of the base spreading the sides of the cover apart as the same is thus forced back and finally entering in slots 65 in the sides of the cover for the purpose of retaining the cover in position.

It will be realized that the short turning feature of the motor truck is particularly advantageous in that it enables the motor truck to be manipulated so as to get it in position beneath platforms which have been loaded in more or less unhandy situations. In the unloading of freight cars, for instance, it is not always possible to place the platform in the most convenient position but this presents no especial difficulties with the present invention, because the truck can be manipulated and turned in such small compass as to enable its being engaged beneath the loaded platform under practically any conditions ordinarily encountered.

What I claim is:

1. In combination, a motor truck provided with lifting jacks and an independent carrier platform having side sills and cross beams connected with said side sills and positioned to be engaged by the lifting jacks of the truck.

2. In combination, a motor truck provided with lifting jacks and an independent carrier platform having side sills and cross beams connected with said side sills and positioned to be engaged by the lifting jacks of the truck in either end to end relation of the truck and carrier platform.

3. In combination, a motor truck provided with lifting jacks, a carrier platform having side sills and cross beams connected with said side sills and positioned to be engaged by the lifting jacks of the truck and supporting feet for the platform having portions secured to the side sills and cross beams to tie the same together.

4. In apparatus of the character described, a motor truck provided with lifting jacks and an independent carrier platform having transverse supports spaced to be engaged by the lifting jacks irrespective of the end of the platform under which the truck enters.

5. In combination with a truck provided with lifting jacks, a carrier platform provided with feet for supporting the same independently of the truck and having transverse beams positioned to be engaged by the lifting jacks in either end to end relation of the truck and platform.

6. In combination, a truck and a carrier platform provided with feet for supporting

the same independently of the truck, lifting jacks on the truck for lifting the carrier platform off its feet when the truck is entered beneath the same, said platform having a frame provided with transverse thrust receiving members positioned to be engaged by the lifting jacks in either end to end relation of the truck and platform.

7. In freight handling apparatus, a motor truck provided with definitely spaced lifting jacks and an independent carrier platform having transverse thrust receiving members arranged in pairs spaced in accordance with the spacing of the lifting jacks and with said pairs spaced equal distances from opposite ends of the platform whereby said truck and platform may be reversibly related end for end.

8. In freight handling apparatus, a motor truck provided with lifting jacks spaced in definite relation and an independent carrier platform having transverse channels spaced in accordance with the spacing of the lifting jacks to form seats therefor.

9. In combination, a truck having an upright end wall or dash, lifting jacks spaced longitudinally on the truck from the end wall and a carrier platform having side sills and transverse beams, the beams being spaced from one end of the truck distances corresponding to the spacing of the jacks from the truck end wall.

10. In combination, a truck having an upright end wall or dash, lifting jacks spaced longitudinally on the truck from the end wall and a carrier platform having side sills and transverse beams, the beams being spaced from each end of the truck distances corresponding to the spacing of the jacks from the truck end wall.

11. In combination, a truck having an upright abutment, lifting jacks spaced longitudinally on the truck from the abutment and a carrier platform having side sills and transverse beams, the beams being spaced from each end of the truck distances corresponding to the spacing of the jacks from the truck abutment.

12. In combination, a truck having an upright resilient abutment, lifting jacks spaced longitudinally on the truck from the abutment and a carrier platform having side sills and transverse beams, the beams being spaced from each end of the truck distances corresponding to the spacing of the jacks from the truck abutment.

In witness whereof, I have hereunto set my hand this 16th day of April, 1920.

WILLARD C. BRINTON.
